(57) **CLAIM**

The ornamental design for a retail fixture, as shown and described.

DESCRIPTION

FIG. 1 is a first isometric view of a retail fixture in accordance with an embodiment of the invention.

FIG. 2 is a second isometric view of the retail fixture in accordance with the embodiment of FIG. 1.

FIG. 3 is a front elevational view of the retail fixture in accordance with the embodiment of FIG. 1.

FIG. 4 is a rear elevational view of the retail fixture in accordance with the embodiment of FIG. 1.

FIG. 5 is a first side elevational view of the retail fixture in accordance with the embodiment of FIG. 1.

FIG. 6 is a second side elevational view of the retail fixture in accordance with the embodiment of FIG. 1.

FIG. 7 is a top elevational view of the retail fixture in accordance with the embodiment of FIG. 1; and,

FIG. 8 is a bottom elevational view of the retail fixture in accordance with the embodiment of FIG. 1.

Any shading on the figures is provided only to distinguish between the flat and contoured portions of the retail fixture, such shading patterns are not intended to be viewed as part of the claimed retail fixture. The evenly-spaced broken lines depict environment and do not form part of the claimed design. The dot-dash broken lines illustrate boundaries and do not form part of the claimed design.

1 Claim, 4 Drawing Sheets
